UNITED STATES PATENT OFFICE.

ANDRIAN I. BARRANOFF, OF BANGOR, MAINE.

STEAM-BOILER.

SPECIFICATION forming part of Letters Patent No. 398,116, dated February 19, 1889.

Application filed July 20, 1888. Serial No. 280,479. (No model.)

To all whom it may concern:

Be it known that I, ANDRIAN I. BARRANOFF, a citizen of the United States, residing at Bangor, in the county of Penobscot and 5 State of Maine, have invented certain new and useful Improvements in Steam-Boilers; and I do hereby declare the following to be a full, clear, and exact description of the invention, such as will enable others skilled in the art to 10 to which it appertains to make and use the same, reference being had to the accompanying drawings, and to letters or figures of reference marked thereon, which form a part of this specification.

15 This invention relates to "steam-boilers," locomotive, stationary, or marine; and it consists in the arrangement of certain pipes and other co-operating parts, by which the circulation in the boiler is increased and the generation of steam to a working pressure is more 20 speedily attained, all substantially as herein-after more particularly set forth and claimed.

The drawings accompanying this specification represent in Figure 1 an end elevation 25 of a boiler embodying my invention, the end plate being removed. Fig. 2 is a sectional elevation longitudinally of a portion of a boiler to which my improvements are applied. Fig. 3 is a section on line $\alpha\alpha$ in Fig. 1, showing 30 the arrangement of pipes at the point where the injectors are located.

In said drawings I have shown an annular tubular boiler, 2, one of that class in which the grate-bars 3 are within the shell of the 35 boiler, while the water-space of the latter surrounds the fire. Horizontal tubular flues 4 are disposed in the usual manner longitudinally therein, and serve to conduct away the hot gases and other products of combustion, 40 through the boiler, as indicated by the arrows, whence they escape by way of the smoke-stack or bonnet 5.

The object of my invention, as before alluded to, is to increase the circulation. To 45 this end I have arranged in duplicate a system of circulating or coil pipes, 6; but as they are alike in structural arrangement and function I shall proceed to describe the operation of a single one. The boiler 2 is annular, 50 composed of two shells—the outer one, 7, and the inner, 8. The latter in the present

instance is eccentrically disposed, as shown, in order to bring the major portion of the water-space 9 above the fire. Through said water-space 9 extend the flues 4, before pre- 55 mised.

At the rear end of the upper water-space, and adjacent to the inner shell, 8, (see Fig. 2,) I have secured to the boiler-head one end of the pipe 6, which is continuous and extends 60 horizontally forward in close proximity to the bridge-wall 10, and being designated at 12. Furthermore, said pipe is coiled or extended in the rear of the bridge-wall by short vertical lengths to produce a large amount of heating-surface within a small space, and is finally 65 united to the outer shell, 7, by the pipe 13, located in a closed chamber, 14, formed by a "jacket," 15, so called, made of cast-iron and secured exteriorly to the boiler-shell at this 70 point. The effect of this pipe or a series of similar pipes is to increase the circulation in the boiler. When the latter is in active service, the hot gases passing over the bridge-wall 10 superheat that portion 12 of the pipe 75 6 in proximity thereto, and since said portion 12 is near the upper water-surface the superheated water naturally passes into the boiler, while an equal quantity emerges from the lower water-space and flows up in the pipe 6. 80 The circulation is accelerated by the length of the pipes 6, whereby a greater heating-surface is presented and the waste heat utilized.

To still further increase the circulation and render it stronger and more rapid, I have located an injector, 16, at the junction of the pipe 13, leading from the boiler, with the lower end of the circulating-pipe 6. From the top of the boiler is led a pipe, 17, which is located in the chamber 14, formed between 90 the outer shell, 7, of the boiler and the jacket 15. This pipe is connected with and feeds the injector 16, while a waste-pipe, 18, which may return to the boiler condense steam from any source, also terminates at the end 95 of the circulating-pipe 6, and is emptied by aid of the injector.

The object of the injector is more readily understood when the boiler has just commenced to make steam, since the latter is first 100 generated above in the steam-space, whence it passes through the pipe 17, and meeting

with the cooler water in the lower water-space, is partially condensed, and thereby induces an upward flow or current through the pipes 13 18 and coil-pipe 6. A greatly-increased circulation is produced—much more so than that produced by the natural rise of the warmer water, ordinarily very slow:

To prevent the hot gases and heat derived therefrom from burning out the upper part of the boiler-head, I have disposed a wall or partition, 19, composed of some good non-conductor of heat, as fire-brick. This wall rests upon proper supports and extends from the boiler-head to the rear end plate, (see Fig. 2,) and is situated about on a plane with the normal water-level. In the chamber so formed is located the feed-pipe 20 of the boiler, provided in that portion within the boiler with fine holes, by which the feed-water is to be delivered in the form of spray.

The operation is as follows, presuming the boiler has just been fired: The circulating-pipes 6, which contain only a small amount of water, soon become heated, as also the water therein—the latter much more rapidly than in the boiler proper. This water at once escapes upwardly through the coil-pipes 6, while a general circulation is at once produced throughout the boiler. Immediately upon production of steam the latter enters the pipes 17 to the injectors, and the circulation is still more accelerated by their activity; hence the working pressure in the boiler is much more quickly obtained.

What I desire to claim is—

1. In an annular boiler, as described, the combination, with said boiler 2, its flues 4 4, the bridge-wall 10 interiorly thereof, and the circulating-pipe 6, which connects the upper and lower water-spaces, and having the horizontal extension 12 in rear of and above the bridge-wall, of the injector 16 and its steam-pipe 17, substantially as specified.

2. The combination, with the boiler 2, bridge-wall 10, the circulating-pipes 6 in rear thereof, which connect the upper and lower water-spaces, and the injectors 16, co-operating with said circulating-pipes, of the jacket 15 and the steam-pipes 17 exteriorly of the boiler, each of which supplies an injector, for purposes substantially as herein set forth.

3. The boiler 2, provided with the flues 4 4, bridge-wall 10, partition 19, and jacket 15, combined with the steam-pipes 17, leading from the steam-space and exteriorly of the boiler to the injectors, and the circulating-pipes 6, which connect the lower and upper water-spaces of said boiler, substantially as herein set forth.

In testimony whereof I affix my signature in presence of two witnesses.

ANDRIAN I. BARRANOFF.

Witnesses:

ALBION VEAZIE,
JOHN C. WILSON.
